UNITED STATES PATENT OFFICE

HARVEY L. BULLOCK, OF ARDSLEY, NEW YORK

SYSTEM FOR LUBRICATING WHEEL FLANGES

Application filed August 16, 1928. Serial No. 299,905.

This invention relates to a system for lubricating the flanges of railway car wheels. It has been recognized for years that lubrication should be provided for the flanges of car 5 wheels particularly at curves in the track; for where the car changes direction in passing about a curve, the flanges are forced sharply against the rail heads with suitable force with the result that both the rails and flanges 10 are subjected to pronounced wear which is frequently accompanied by considerable noise.

Because of wear occasioned in the manner described, it is necessary to frequently change 15 the wheels on cars and this is particularly true on switch engines which are almost constantly traveling over curves and frogs and otherwise changing direction. The renewal and replacement of wheels for the reasons 20 stated constitutes an appreciable part of the maintenance of railway rolling stock and aside from the expense entailed in this operation also necessitates the removal of cars or locomotives from service to permit of their 25 reconditioning in the manner stated.

Numerous attempts have been made to eliminate the wear to which I have referred. For example, it has been suggested to provide a tank of oil and another tank of compressed air and to so control the feed of oil and compressed air from the respective tanks 30 that the oil will be fed upon the peripheries of the wheels while the wheels are traversing a curve. In all of these devices, however, the arrangement has been such that the oil started to feed under the action of compressed air as soon as the car or locomotive 35 wheels reached the curve and continued to flow until the wheels had completely traversed the curve and again reached a straight portion of the track. It is not uncommon for a curve to be quite extensive and it is therefore obvious that in such prior arrangements, 40 great quantities of oil were fed at each curve, so that in the first place it was not only practically impossible to keep a sufficient oil supply, but the further and more serious difficulty was inherent in the fact that so much oil was fed that it not only coated practically 45 all of the running gear of the car or locomo-

tive, but also formed a film of oil on the tread of the wheel with which the brakes are called upon to cooperate in such manner as to preclude braking of the train. As a matter of fact, the oil was fed in such quantities as to lubricate the brake shoes so that it was practically impossible to stop the train. This difficulty will result even though oil is fed under combined hydrostatic and pneumatic pressure or under hydrostatic pressure with an admixing and spraying with compressed air. As a result the most satisfactory method known to the art, prior to this invention, is to employ trackwalkers who periodically manually apply grease by means of daubers, 55 brushes or the like to the tracks at the curves and frogs. No satisfactory mechanical or automatic means has yet been produced for solving the problem to which I have referred.

My study and deliberation have convinced me that the elimination of excessive wear on wheel flanges can only be practically and satisfactorily overcome by the lubrication of these flanges in contradistinction to lubrication of the rails. Satisfactory distribution 60 of lubricant on a rail is not practically feasible because of the relatively extensive character of the rail surface at long sweeping curves. My experience has shown me that far more satisfactory results can be obtained 65 by actually lubricating the flanges which it is desired to primarily protect against excessive wear and experiments have convinced me that this is not only feasible and practical, but that it can be more economically and efficiently carried out than the lubrication of the 70 rails.

The object of the present invention, therefore, is to provide novel and efficient means for lubricating wheel flanges on cars, locomotives, etc., and it is preferred that this lubrication be automatic, so that the lubricant may be conserved as much as practical. Furthermore, an equally important object of the invention is to so lubricate flanges of the 75 wheels that only sufficiently amount of lubricant is applied to eliminate the wear and insufficient lubricant is supplied to interfere with proper functioning of the brakes or to bring about a distribution of the lubricant 80

throughout the running gearing of the car.

It is the purpose of the present invention, therefore, to provide for the automatic application of a relatively small predetermined amount of lubricant to the flanges of the wheels and to control the feed of such lubricant in such manner that it will be fed while the wheels are traversing a curve in the track without, however, necessarily feeding the lubricant throughout the full extent of the curve. Thus I am able to obtain proper lubrication in a thoroughly automatic manner without the difficulties inherent in the automatic structures heretofore suggested.

In practically carrying out the invention, it is found that the best results are obtained by atomizing the lubricant preferably in the form of a fine spray upon the wheel flanges. This may be accomplished in practice by providing a suitable source of lubricating means adapted to be fed by means of compressed air from a suitable source through nozzles positioned in proximity to the wheel flanges, so that at desired times, a predetermined measured quantity of lubricant may be entrained in a quantity of compressed air which is freed in the direction of the wheel flanges to atomize the lubricant in the form of mist upon said flanges. Thus in practically carrying out the invention, suitable nozzles are juxtaposed with the wheel flanges and are fed from a suitable source of lubricant and compressed air and the passage of lubricant and compressed air to these nozzles is preferably controlled in an automatic manner, so that as the car starts to turn a curve, such predetermined quantity of oil together with compressed air are fed to the nozzles to lubricate the flanges as stated.

Prolonged tests under operating conditions have shown that the system of this invention will adequately lubricate the wheel flanges and materially increase their length of service without causing gumming of the running gear or improper functioning of the brakes.

Features of the invention, other than those specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a diagrammatic view showing certain parts in section and illustrating a system embodying the present invention.

Figure 2 shows in section certain valve mechanism illustrated with the parts in different positions in Figure 1.

Referring to the drawings, 1 designates a car axle having associated wheels 2 provided with the usual flanges 3 and adapted to run

on rails 4 which collectively constitute the track.

Mounted on the car with which the wheels 2 are associated is a valve casing 5. This valve casing may be of any appropriate shape or configuration and may be constructed of one or more parts. For the purpose of illustration, however, I have shown it of substantially inverted T shape and as provided with three arms 6, 7 and 8 which are substantially tubular. The arms 6 and 7 are in alinement while the arm 8 is at substantially right angles thereto. Each of the arms 7 and 8 are provided with valve seats 9, 9^a and 10, respectively, while the arm 6 is formed with a stop 11.

Adapted for cooperation with the seats 9 and 9^a is a ball valve 12 and cooperating with the seat 10 is a ball valve 13. Mounted to slide within the arm 6 is a piston 14 preferably provided with a suitable packing 15 and extending from the forward end of this piston is a push rod 16 adapted when the piston is moved to the extreme right in Figure 1 to unseat the valve 12 from seat 9 and force it against seat 9^a, as shown in this figure.

Positioned below the valve 13 in the arm 8 is another push rod 17 which is adapted to be operated by a cam surface 18 formed on the forward end of the piston 14, so that when the piston moves to the right from the position shown in Figure 2 the lower end of the rod 17 will be forced up by the surface 18 and will thus engage the valve 13 and force it from its seat as shown in Figure 1.

Associated with the valve casing which I have described are suitable sources of compressed air and a lubricating medium. The source of compressed air is designated 19 and may, if desired, be the main compressed air reservoir with which cars and locomotives are usually provided, although a separate source of compressed air may be utilized if desired. From the reservoir 19, a pipe 20 extends to a T 21 and in this pipe is included a reducing valve 22 and a shut off valve 23.

One branch of a T is connected by a pipe 24 to another T 25 one branch of which is connected by a pipe 26 to a valve chamber 27 of the valve 13. The other branch of the T 25 is connected by a pipe 28 to a lubricating reservoir 29 with which charging apparatus 30 is associated. The base of the tank 29 is connected by a pipe 31 with a check valve 32, which, in turn, communicates with the valve chamber 33 of the valve 12. A spring 34 normally maintains the check valve in engagement with its seat 35.

The T 21 is connected to the cylinder back of the piston 14, but in this connection, suitable control means is positioned so that the admission of compressed air into said cylinder may be properly controlled. This means may partake of different forms, but, in the showing of the drawings, the pipe 36 leads

from the T 21 to the casing 37 of a magnetic valve which is diagrammatically illustrated in the drawings. This casing has two opposed valve seats 38 and 39. A valve 40 cooperates with the former and the valve 41 with the latter and these two valves are connected together by a rod 42, while a valve stem 43 connects both of the valves to the core 44 of a solenoid having a winding 45. A spring 46, normally elevates both valves to seat the valve 41 and unseat the valve 40, but when the coil 45 is energized, the core 44 will be depressed to its magnetic center and will overcome the tension of the spring 46 to seat the valve 40 and unseat the valve 41. The pipe 39 communicates with the chamber 47 of the valve 41, while the chamber 48 of the valve 40 is vented as shown at 49. The rod 42 extends loosely through a passage 50 and this passage is connected by a pipe 51 to the cylinder in which the piston 14 operates.

The coil 45 of the magnet valve is included in a circuit 52 which also includes a suitable source of power 53 and a switch 54. This switch may be of different forms and may, if desired, be manually controlled, but, for the purpose of illustration, I have shown an automatic switch embodying a switch arm 55 pivoted at 56 and having leaves 57 and 58 which work between contacts 59.

When the switch arm is in neutral position as shown in dotted lines in Figure 1, the leaves 57 and 58 will be free from both contacts 59, but if the switch arm is swung into either direction as, for example, into the full line position of this figure, one of the leaves will engage one of the contacts and complete a circuit through the core of the solenoid. In the construction shown, the switch 54 may be conveniently mounted upon the draw bar support of the car or locomotive, and the switch arm 55 may be connected by a spring 60 to the end frame 61 of the adjacent wheel truck, so that when the car is traveling along a straight track, the switch arm will be held in neutral position, but as soon as the car starts to traverse a curved track relative movement between the truck and the draw bar support will bring about a pivotal movement of the switch arm with consequent completion of the magnet valve circuit.

It will be noted that the rod 16 which controls the valve 12 fits loosely through a passage 62 in the valve casing and this passage is connected by means of a pipe 63 to a chamber 64, which, is, in turn, connected by flexible tubes 65 and 66 to nozzles 67 and 68 suitably supported in cooperative relation to the flanges of the wheels 2. Additional flexible tubes lead to other nozzles positioned adjacent the flanges of the other wheels of the same truck and other tubes may also lead to the flanges of the other trucks of the car or locomotive, so that all the wheels of the par-

ticular car or locomotive may be incorporated in the one system.

The operation of the system for the carrying out of its functions will now be described.

Under normal conditions, air under pressure is contained in a reservoir 19. Suitable lubricant such as oil is contained in the reservoir 29. The valve 12 will be in engagement with the seat 9 and the pressure of air through the pipe 28 will have forced sufficient lubricant from the tank 29 past the check valve 32 to fill the chamber 33, the space 33^a and the space 33^b with lubricant. When these spaces are filled the spring 34 will seat the check valve 32 thereby leaving a portion of the oil within these spaces isolated from the oil in the tank 29. During this normal period of inactivity, the valve 40 is unseated and the valve 41 seated and the valves of the valve casing 5 are in the positions shown in Fig. 2. This will be the normal positions of the parts, while the car is traveling along a straight track. When the car starts to make a turn, the act of turning the curve automatically brings about movement of the switch arm 55 from its normal neutral dotted line position into the position shown in full lines in Fig. 1, thereby resulting in energizing the circuit 52. The core 44 is immediately drawn down to close the valve 40 and unseat the valve 41.

As a result, air from the reservoir 19 is fed through the pipes 20, 36 and through the valve casing 37 and pipe 51 to the cylinder of the valve casing 5 and operates upon the piston 14, thereby forcing the piston to the right. During the movement of this piston to the right, the rod 17 is elevated to unseat the valve 13, while the rod 16 is operated to unseat the valve 12 from seat 9 and force it to seat 9^a. Immediately the valve 13 is unseated, compressed air is fed through the pipes 24 and 26 into the valve casing and past the valve 13 into the passage 62 and thence through the pipe 63 into the chamber 64.

When this operation occurs, the forcing of the valve 12 to its seat 9^a by the piston stem 16 positively isolates that portion of the oil which is contained in the space 33 from the other oil in the spaces 33^a and 33^b and this portion of the oil which has been isolated in the space 33 is picked up by the compressed air as it rushes through the casing and out through the passage 63 to the chamber 64, so that this oil is entrained with the compressed air and carried therewith to the chamber 64 which constitutes a mixing chamber. Particular attention is directed to the fact that by the isolation of this quantity of oil in the space 33, I bring about the feed of a predetermined measured quantity of oil at each operation of the device because the valve 12 remains in engagement with its seat 9^a as long as there is pressure back of the piston

14 and thus no more oil can pass through from the tank 29 after this predetermined amount has been fed until the next operation of the apparatus which occurs when the next curve is reached.

From this mixing chamber 64, oil and air pass through the flexible connections 65 and 66 to the nozzles 67 and 68 and by virtue of the presence of air pressure, this oil is atomized in a fine spray on to the flanges of the wheels. Thus the oil is economically fed to the flanges and thoroughly lubricates said flanges, while the car or locomotive is traversing a curve. As soon as the car reaches a straight portion of the track beyond the curve, the switch arm 55 again assumes its neutral position and the piston will be retracted.

It will be apparent that in this connection, as soon as the circuit 52 is broken by movement of the switch arm into neutral position, the spring 46 will seat the valve 41 and unseat the valve 40, thereby venting the cylinder and the piston will thereupon be forced by the rods 17 and 16 to the left in Fig. 1 to permit the valve 12 to engage seat 9 and valve 13 also to seat and shut off the flow of compressed air. The flanges will be left sufficiently lubricated to maintain this condition until another curve is reached whereupon further lubrication of these flanges occurs.

My experience with a system of this character has shown me that it is thoroughly efficient in the carrying out of its intended purposes. It is economical in the use of lubricant and minimizes the wear to which I have hereinbefore referred. The drawings show a system which has been found in practice to give thoroughly satisfactory results and while I have described the piping connections in great detail in order that the invention may be fully understood, I am aware that these piping connections may vary within wide limits without departing from this invention, the essential consideration being that a predetermined measured quantity of lubricant be fed by compressed air to the nozzles in a manner to lubricate the wheel flanges by either automatic or manually controlled means.

The foregoing detailed description sets forth the invention in its preferred practical form and the invention is to be understood for the reasons stated as fully commensurate with the appended claims.

I wish to call attention to the fact that when wheel flanges are lubricated in the manner described, wear is not only minimized on the flanges, but lubricant from the flanges is also deposited on the rails and serves to protect the rails against wear. My experience has shown further that by properly lubricating these cooperating parts, the tendency of derailment at frogs, switches or at curves is

minimized and travel rendered more safe than heretofore.

Having thus fully described the invention, what I claim as new and desire to secure by Letters Patent is:

1. In a system for lubricating the flanges of car and locomotive wheels, a suitable source of lubricant, a suitable source of compressed air, nozzles positioned adjacent the wheel flanges, a mixing chamber, a conduit leading from the mixing chamber to the nozzles, conduits leading from the sources of compressed air and lubricant to the mixing chamber, a valve in each of said latter conduits, and a pneumatically operated piston for opening one valve to feed a predetermined amount of lubricant into the mixing chamber from the source of lubricant supply and for simultaneously opening the other valve to feed sufficient compressed air into the mixing chamber to be admixed with the lubricant therein and to pneumatically feed such lubricant to and through the nozzles whereby the lubricant is atomized upon the wheel flanges.

2. In a system for lubricating the flanges of car and locomotive wheels, a suitable valve casing, a source of compressed air, a source of lubricant, means for conveying compressed air and the lubricant from their respective sources to the valve casing, nozzles positioned adjacent the wheel flanges, conduits leading from the nozzles to the valve casing, valves within the valve casing for controlling the feed of lubricant and compressed air to the nozzles, the valve which controls the feed of lubricant being adapted to feed only a predetermined, relatively small quantity of the lubricant at each operation of said valve, and a pneumatically operated piston for simultaneously controlling said valves to permit the simultaneous passage of compressed air and a predetermined quantity of lubricant to the nozzles.

3. In a system for lubricating the flanges of car and locomotive wheels, a suitable valve casing provided therein with a cylinder, a source of compressed air, a source of lubricant, means for conveying lubricant and compressed air from the respective sources to the valve casing, nozzles positioned adjacent the wheel flanges, conduits leading from the valve casing to said nozzles, valves within the valve casing for normally precluding the passage of compressed air or lubricant to the nozzles, a piston in the cylinder of the valve casing operable to simultaneously unseat both of said valves when compressed air is admitted back of the piston, and means for permitting the admission of compressed air into the cylinder back of the piston.

4. In a system for lubricating the flanges of car and locomotive wheels, a suitable valve casing provided therein with a cylinder, a source of compressed air, a source of lubricant, means for conveying lubricant and com-

pressed air from the respective sources to the valve casing, nozzles positioned adjacent the wheel flanges, conduits leading from the valve casing to said nozzles, valves within the valve casing for normally precluding the passage of compressed air or lubricant to the nozzles, a piston in the cylinder of the valve casing operable to simultaneously unseat both of said valves when compressed air is admitted back of the piston, and valvular means for controlling the admission of compressed air into the cylinder back of the piston.

5. In a system for lubricating the flanges of car and locomotive wheels, a suitable valve casing provided therein with a cylinder, a source of compressed air, a source of lubricant, means for conveying lubricant and compressed air from the respective sources to the valve casing, nozzles positioned adjacent the wheel flanges, conduits leading from the valve casing to said nozzles, valves within the valve casing for normally precluding the passage of compressed air or lubricant to the nozzles, a piston in the cylinder of the valve casing operable to simultaneously unseat both of said valves when compressed air is admitted back of the piston, and valvular means for controlling the admission of compressed air into the cylinder back of the piston, and electrical means controlled by pivotal movement of the wheels on a vertical axis (as when turning a curve) for operating the valve to admit compressed air into said cylinder.

6. In a system for lubricating the flanges of car and locomotive wheels, a suitable valve casing provided therein with a cylinder, a source of compressed air, a source of lubricant, means for conveying lubricant and compressed air from the respective sources to the valve casing, nozzles positioned adjacent the wheel flanges, conduits leading from the valve casing to said nozzles, valves within the valve casing for normally precluding the passage of compressed air or lubricant to the nozzles, a piston in the cylinder of the valve casing operable to simultaneously unseat both of said valves when compressed air is admitted back of the piston, and a magnetic valve operable upon pivotal movement of the wheels on a vertical axis (as when turning a curve) to admit compressed air into said cylinder.

7. In a system for lubricating the flanges of car and locomotive wheels, a suitable valve casing provided therein with a cylinder and also a measuring chamber, a source of compressed air, a source of lubricant, means for conveying lubricant and compressed air from the respective sources to the valve casing to cause the lubricant to normally fill the measuring chamber, nozzles positioned adjacent the wheel flanges, conduits leading from the valve casing to said nozzles, a valve within the valve casing for normally precluding the flow of compressed air into the valve casing, a valve also in the casing for normally allow-

ing the flow of lubricant into the measuring chamber, but precluding the flow of lubricant from the measuring chamber to the nozzles, and a pneumatically operable piston for operating said valves to open the valve which controls the flow of compressed air and to also open the valve to permit the passage of lubricant from the measuring chamber into the flow of compressed air through the valve casing and simultaneously shut off the flow of lubricant from the source of supply into the measuring chamber.

8. In a system for lubricating the flanges of car and locomotive wheels, a suitable valve casing provided therein with a measuring chamber, a source of compressed air, a source of lubricant, means for conveying lubricant and compressed air from the respective sources to the valve casing to cause the lubricant to normally fill the measuring chamber, nozzles positioned adjacent the wheel flanges, conduits leading from the valve casing to said nozzles, a valve within the valve casing for normally precluding the flow of compressed air into the valve casing, a valve also in the casing for normally allowing the flow of lubricant into the measuring chamber, but precluding the flow of lubricant from the measuring chamber to the nozzles, a piston in the cylinder of the valve casing operable to simultaneously unseat both valves to permit compressed air to flow through the valve casing and lubricant to pass from the measuring chamber into the flow of compressed air and to simultaneously shut off the flow of lubricant from the source of lubricant to the measuring chamber, when compressed air is admitted back of the piston, and means operable upon pivotal movement of the wheels on a vertical axis (as when turning a curve) to admit compressed air into said cylinder.

In testimony whereof I have signed the foregoing specification.

HARVEY L. BULLOCK.
